SECOND FOLD ROLLER

Frank A. Foster, Melrose Park, Ill., assignor to The
Gess Printing Press Company, Chicago, Ill., a
corporation of Illinois

Application June 27, 1945, Serial No. 601,895

7 Claims. (Cl. 270—76)

1

The present invention relates to printing presses and refers more particularly to the folding rollers for imparting the second or lateral fold to newspapers or other products of rotary printing presses.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Figure 1 is a front elevation of the folder assembly, the central portion thereof being broken away.

Figure 2 is a side elevation thereof, partly in section along the line 2—2 of Figure 1.

Figure 3 is a longitudinal vertical section along the line 3—3 of Figure 2.

Figure 4 is a section along the line 4—4 of Figure 3.

Figure 5 is a section along the line 5—5 of Figure 2.

These second fold rollers must be able to operate at various distances from each other in order to handle products of varying thickness; and the problem of driving them in their various positions has had numerous solutions. All of such solutions involve mounting each of the second fold rollers for rotation about its own axis and also for pivoting about an axis distinct from its own. A desirable simplicity of design is achieved by mounting the rollers on bell cranks, the rollers being driven by intermediate gears mounted on the extremities of the opposite arms of the cranks. In such construction however perfect mesh is not maintained between the gear train throughout the range of necessary adjustment. Perfect mesh has been obtained by providing adjustment of the second fold rollers consisting in a pivoting motion about the axis of intermediate rolls driving them, but such constructions involve undesirable multiplicity of parts.

The principal object of the present invention is to provide a second fold roller unit construct-

2

ed simply and sturdily of few parts and adapted to maintain gear mesh through a wide range of adjustment.

A further object is to provide greater access to the delivery mechanism by the use of a more compact second fold roller construction.

A further object is to provide greater working clearance through the framework of the folder in case of choke.

10 Other objects will become apparent in the course of the following specification.

In accordance with the illustrative embodiment of the present invention, there is provided a second fold roller unit in which the rollers pivot for adjustment about the axis of the folding cylinder and are driven by a gear concentric therewith.

The rollers are urged into a predetermined adjustable relative position by resilient means adapted to yield in case of choke, and these means 20 slant upward and outward from the lower extremities of the lever arms supporting the rollers, the slanting position affording greater working clearance to an operator seeking to relieve a choke.

25 In operation, as the distance between the two second fold rollers is adjusted by well known mechanism, they move toward or away from each other along the arcs of circles centred on the folding cylinder axis, and their gears thus maintain 30 constant mesh with the driving gear which is coaxial with the cylinder. It is notable that no extra drive shafts are required in this construction, the one driving and two driven gears being mounted on existing cylinder and roller shafts respectively, except for the inevitable intermediate gear on a stub shaft for reversing the direction of one of the two folding rollers. The construction thus affords more working space through the folder frame, a more rigid assembly, and one which 35 can be assembled and dismantled with greater ease than heretofore.

It will be understood that the foregoing general description and the following detailed description as well are exemplary and explanatory 40 of the invention but are not restrictive thereof.

Referring now in detail to the illustrative embodiment of the invention as shown in the drawings, the folding cylinder 1 is carried by a shaft 2 in antifriction bearings 3, 4 in bearing sleeves 50 5, 6 fixedly mounted by means of screws 7 and connecting plates 8 or otherwise in the split journal blocks 9, 10 comprised by the cross reaches 11, 12 of the folder frame of the press. Shaft 2 also carries exteriorly of cross member 11 gear 55 13 which connects it in conventional manner to

the press gearing, not shown. A flanged cam plate 14 fits over the inner end of bearing sleeve 5, being held thereon by end plate 15 and screws 16. Plate 14 has a substantially cylindrical bearing surface 17 substantially in extension of a similar surface 18 on bearing sleeve 5.

Rotatably mounted on bearing surface 18, which is coaxial with shaft 2, is lever arm 19, near the lower extremity of which an end of shaft 20 of second fold roller 21 is rotatably journalled in antifriction bearing 22. The opposite end of shaft 20 is similarly mounted in bearing 23 in lever arm 24 similarly mounted on bearing surface 25 of bearing sleeve 6.

The other second fold roller 26 is supported similarly on shaft 27 in bearings, not shown, similarly located in lever arms 28, 29 journalled on bearing surfaces 17, 25 respectively, coaxially with shaft 2. Lever arm 29 additionally carries stub shaft 30 for intermediate gear 31.

Roller drive gear 32 is coaxially mounted on shaft 2 by means of a collar portion 33 fixed against rotation by drive plate 34 and screws 35. Roller gear 36 on shaft 20 and intermediate gear 31 on stub shaft 30 engage drive gear 32, and intermediate gear 31 further engages roller gear 37 on shaft 27. As clearly seen from Figure 5, roller gears 36, 37 do not mesh with each other.

Choke relief means are provided as follows. The lower extremities 38 of lever arms 19, 28, 24, 29 are formed with slots 39 in which spring plungers 40 are slidable, the extremities further comprising threaded ears 41 in which adjusting screws 42 are engaged. Pivot pins 43 bushed in bores in the cross reaches 11, 12 are bored transversely as at 44 to receive plungers 40 and have portions 45 extending beyond the bores 44 against which the adjusting screws 42 may bear. The midpoint of slots 39 is higher than the axis of pins 43, so that plungers 40 in extending outward from the latter through the former, slant upward. Two spring seat collars 46, 47 are slidable on each plunger 40 and jointly provide spring seats for compression coil springs 48, collar 46 being urged against extremity 38 by the spring, collar 47 being adjustably retained by nut 49 on threads 50.

Conventional adjustment of the rollers relative to each other and to the vertical plane through the axis of the folding cylinder is provided by the adjusting rods 51, 52 each of which has an end portion formed with right and left handed threads 53, 54 respectively on which are threadedly engaged adjusting stops 55, 56 comprising laterally extending cylindrical lugs 57 engaging corresponding recesses 58 in lever arms 19, 28, 24, 29. Rods 51, 52 are rotatably supported in arms 59, 60 of standards 61, 62, the two latter rotatably supporting the worm rod 63 carrying worm 64, worm 65 being carried by a sleeve 66 rotatable on rod 63 and being connected to handwheel 72 while handwheel 71 is mounted on rod 63.

It is obvious from the above that the second fold rollers 21, 26, being mounted to pivot for adjustment about the axis of folding cylinder 1, will at all positions of adjustment and of choke relief be at the same distance from said axis and thus will maintain constant mesh between their driven gears 31, 37, 38 and the roller drive gear 32 which is coaxial with cylinder 1. It is also obvious that the spring plungers 40 and springs 48 provided for choke relief afforded greater working clearance through the folder frame in case of choke by reason of being slanted upward in their outward extension from their pivots 43.

The invention in its broader aspects is not limited to the specific mechanisms shown and described but departures may be made therefrom with the scope of the accompanying claims without departing from the principles of the invention and without sacrificing its chief advantages.

What is claimed is:

1. A second fold roller construction or the like comprising, in combination with a folding cylinder, a pair of second fold rollers, said rollers being mounted to pivot about the axis of said cylinder, a roller drive gear mounted coaxially with said cylinder and roller gears mounted coaxially with said rollers and driven from said roller drive gear.

2. A second fold roller construction or the like comprising, in combination with a folding cylinder, a pair of second fold rollers, said rollers being mounted to pivot about the axis of said cylinder and a roller drive gear mounted coaxially with said cylinder and engaging gears connected to said rollers.

3. A second fold roller construction or the like comprising, in combination with a folding cylinder, bearing sleeves adapted to receive the shaft of said cylinder and rotatably support same, said sleeves having exterior bearing surfaces, lever arms mounted on said bearing surfaces, second fold rollers or the like rotatably mounted near the extremities of said lever arms and a roller drive gear mounted coaxially with said cylinder and engaging gears connected to said rollers.

4. A second fold roller construction or the like comprising, in combination with a folding cylinder, bearing sleeves adapted to receive the shaft of said cylinder and rotatably support same, said sleeves comprising exterior bearing surfaces, lever arms mounted on said bearing surfaces, second fold rollers or the like rotatably mounted near the extremities of said lever arms, a roller drive gear mounted coaxially with said cylinder, roller gears mounted coaxially with said rollers, and an intermediate gear mounted on a stub shaft on one of said arms and connecting one of said roller gears to said roller drive gear, the other of said roller gears engaging said roller drive gear directly.

5. A second fold roller construction or the like comprising, in combination with a folder frame, a folding cylinder and second fold rollers mounted to pivot on lever arms about the axis of said cylinder, choke relief means comprising coiled springs urging said rollers towards each other by engaging said lever arms and diverging at an angle less than the angle of divergence of lines normal to the cylinder radii on which the roller axes lie.

6. A second fold roller construction or the like comprising, in combination with a folder frame, a folding cylinder and second fold rollers mounted to pivot on lever arms about the axis of said cylinder, choke relief means comprising coiled springs urging said rollers towards each other by engaging said lever arms and diverging at an angle less than the angle of divergence of lines normal to the cylinder radii on which the roller axes lie.

7. Choke relief means for a second fold roller construction or the like comprising, in combination with a folding cylinder, second fold rollers mounted to rotate on axes adjacent said cylinder and pivotal mounting means for the same, coiled springs engaging said mounting means to urge said rollers toward each other and diverge-

ing at an angle less than the angle of divergence of lines normal to the cylinder radii on which the roller axes lie.
